UNITED STATES PATENT OFFICE

LUKE J. FAIRBANKS, OF LOS ANGELES, CALIFORNIA

CONTAINER AND MEANS FOR HOLDING SAID CONTAINERS IN COOPERATION

Application filed March 19, 1927. Serial No. 176,862.

This invention relates to containers and means for holding the said containers in cooperation.

An object of the invention is to hold two dishes, the rims of which are of like diameter, in cooperative relation, and in such a manner that foodstuffs may be contained in either or both of the dishes without any danger of spilling and regardless of rough treatment. 10 Another object is the provision of a device which is particularly adaptable for salesmen's use, in that one of the dishes may carry the particular commodity handled by the salesman, and the other dish, when released 15 from the first dish, may hold other goods or commodities for the purpose of making comparisons between the commodities.

Another object is the provision of a device of the character stated which will hold two 20 dishes or the like in close cooperative relation, so that the contents of said dishes cannot be spilled, and in such a manner that the air within the dishes is not compressed, whereby the liability of leakage is in a measure over- 25 come.

Other objects include a device which is simple of structure, economical of manufacture, and generally superior in use and service.

With the above and other objects in view, 30 the invention consists in the novel and useful provision, formation, construction, association and relative arrangement of parts, members and features, all as shown in certain embodiments in the accompanying drawing, described generally, and more particularly 35 pointed out in the claims.

In the drawing:

Figure 1 is a perspective view of two dishes 40 and means for holding the dishes in cooperative relation;

Figure 2 is a vertical sectional view of the dishes, and holding means, shown in Fig. 1;

Figure 3 is a plan view of the showing of 45 Fig. 1, with the holding means released;

Figure 4 is a front elevation of the invention;

Figure 5 is an elevation of one of the pans or dishes;

Figure 6 is a fragmentary and cross-sectional view of two of the dishes or pans and a gasket; and 50

Figure 7 is a view similar to Fig. 6, and showing the pans in cooperation with the gasket and the holding means. 55

Corresponding parts in all the figures are designated by the same reference characters.

Referring now with particularity to the drawing, the improved device shown in Fig. 1 is designated as an entirety by A, and the same includes two pans or dishes a and b, the rims of which are of like diameter, and in each instance the rim is curved as shown at 1 and 2. The pans may have different depths, as indicated in Fig. 4, the pan c having a depth equal to the pan a. In other words, to form the device I use two pans, one of which pans is inverted upon the other of said pans, so that the rims are adjacent or in cooperation. I likewise provide a gasket d adapted to be received between the rims of said pans. 60

This gasket is so formed as to be carried by the rim of one of said pans, for instance, the pan b, as shown in Fig. 6. The gasket d is annular in form, and provided with a curved 65 annular slot 3, adapted to receive the curved rim 1. The base of said gasket is formed with an annular concavity 4. It will thus be seen that the portion 5 of the gasket between the slot 3 and the concavity 4 is substantially 70 wedge shape, the thickest portion of said wedge lying outwardly from the rim of the pan or dish, and the thinner portion approaching the inner confines of the dish. When the two dishes a and b are placed together, it will be seen that the concavity 4 75

acts as a cap to center the rim of the dish a, and that the thinnest portion of the wedge-like part of the gasket is received within the two rims. In order to secure the two dishes 80

so that they can be separated readily, I have provided the holding means *e*, which includes a band *6* provided with U-shaped clips *7*, and with locking means designated generally as *8*.
 5 This locking means includes a member *9*, fastened to the band adjacent an end thereof, which has a serrated or hook portions *10*. The opposite end of the band is looped at *11*, to confine a member *12*, comprising a wire member having an intermediate portion *13* passed through the loop *11*, and two leg portions *14* and *15*, having inwardly directed end portions *16* and *17*, associated with a clasp *18*. The clasp *18* is provided with a
 10 plate *19*, which is formed with openings adapted to receive the ends *16* and *17*. It is to be noted that this plate *19* is located between the ends of the clasp, and one end of said clasp is provided with a pin *20*. In this
 15 connection it is to be noted that the said clasp includes a plate having two side walls *21* and *22*, and an intermediate connecting wall *23*, this connecting wall *23* being curved, so as to correspond to the curvature of the
 20 periphery of the rim of the dishes. Furthermore, the said pin *20* is received between the sides *21* and *22*.

The operation of the device is as follows:
 30 Assume that the pans *a* and *b* are used, and that the pan *b* is carrying the gasket *d*. When the two pans are in cooperation the holding means *e* may then be adjusted so as to hold the two pans in cooperative relation. This is done by passing the band around the
 35 gasket in the manner shown in Fig. 3, wherein it will be seen that the U-shaped members *7* straddle the gasket and the rims of the pans. The band is pressed inwardly so that the pin *20* may engage one of the serrations or hooks *10* of the member *9*, and upon depressing the
 40 clasp *18* the band is caused to engage the outer face *24* of the gasket. Inasmuch as the gasket is so constructed as to have a portion extending outwardly from the rims of the respective pans, as shown at *25*, this locking of the band will tend to force the wedge portion of the gasket between the rims of the pans. In a measure this will tend to separate the pans
 45 slightly, and the separation of the pans will not cause compression of the air within the pans, with the result that there is less likelihood of any commodity therein leaking as between the gasket and the rims of the respective pans. It can be readily seen that the clasp in cooperation with the member *9* is cam-like in action, in that when the plate of the clasp is pushed downwardly so as to lie
 50 adjacent the band *6*, that the diameter of the band is lessened. In this manner the degree of tightness of the engagement of the band with the gasket may be regulated. One of the important features of this invention is the
 55 fact that the wedge portion of the gasket is

forced between the rims of the respective pans or dishes.

Any desired pan or dish might be used, the main essential being that where two dishes or pans cooperate the rims be of like diameter. Assuming an actual use for the invention, a salesman might wish to demonstrate the superiority of a certain brand of canned peaches over other brands. One of the cans is opened, and the contents placed, say in the dish *a*.
 75

The other pan *b* is then locked to the pan *a*. Upon reaching a buyer, or a grocery store, the pans are released and he shows the contents to the grocer. The grocer is permitted to sample one of the peaches, and if he remarks that they are not superior to any other brand of peaches that he now carries, the salesman may ask the grocer to open a can of the other brand of peaches and place them in the dish *b* for the purpose of comparison. After this has been done the salesman may cover the pan *a* with another pan, or the pan *c*, and he may journey to another grocer or buyer and allow him to sample the peaches. As frequent samplings would possibly ruin the appearance of the contents, he may open another can of peaches and place them in the dish *a*. Thus an actual saving results, in that the salesman does not have to carry one can the contents of which have been partly used and then open a new can. With this method the commodity is presented in its most attractive form.

The invention is likewise useful for picnics, in that the different commodities may be placed in the pans, and when the top pan is removed it can be used as a dish, so that each set or pair of pans that have been locked together furnishes two dishes, and still provides for the commodity. Roast chicken may be carried by my invention by providing two pans of proper depth locked together. It is also evident that the gasket acts as a continuation for one of the dishes, and functions as a cover for the rim of the other dish.

It is perhaps unnecessary to state that the portion *26* of the band is pressed against the outer face of the gasket, and the position of the member *9* is such that this portion *26* will at all times engage the gasket so as to compress that portion of the gasket which would lie between the member *9* and the first member *7*.

It is obvious that various changes and modifications and variations may be made in practising the invention in departure from the particular showing, without departing from the true spirit of the invention.

Having thus disclosed my invention, I claim and desire to secure by Letters Patent:
 1. Means of the character disclosed, including a pan formed with a curved rim, an annular gasket, provided with a slotted portion to receive said curved rim, said gasket being provided with an annular concavity and

whereby said gasket, due to said concavity, may center the said container upon the rim of a second container.

2. Means of the character disclosed including a pan formed with a rim, a gasket secured to the rim, and provided with a concavity and whereby said gasket due to said concavity may center the said container upon the rim of a second container, and means for locking said second container to the first container when so positioned.

In testimony whereof, he has signed his name to this specification.

LUKE J. FAIRBANKS.
